ROTARY SWITCH FOR RAILWAY SIGNALING SYSTEMS

John P. Slay, Silver Spring, Md.

Application December 14, 1950, Serial No. 200,779

1 Claim. (Cl. 200—14)

This invention comprises novel and useful improvements in an electric signaling system for toy railways, and more specifically pertains to a novel system of signal lights for grade crossings, and the like, for toy railways, together with improved circuit means and circuit control means for selectively operating the lights by the approach of a train to a first switch and the departure of the train from the other switch.

The principal object of this invention is to provide an improved electrical signaling system which will automatically control a single signal light or a pair of signal lights to indicate the approach of a train or the departure of the train from the vicinity of the signal lights.

A further object of the invention is to provide an electric signaling system which shall be of general application not only to toy railways but for electrical signaling for railways in general, and for electric signaling in general.

Yet another important object of the invention is to provide an electric signaling system specifically adapted for use with toy railways which shall have an exceedingly simple, yet dependable and durable construction as to its moving parts.

A still further object of the invention is to provide an electrical signaling system which shall enable a signal light to be operated automatically upon the approach of the train, and the light darkened upon the departure of a train therefrom.

Yet another object of the invention is to provide an electrical signaling system in conformity with the preceding object wherein a pair of lights are alternately operated automatically in response to movement of a train, a first light being illuminated upon the approach of a train and darkened upon its departure, while the second light is operated in the reverse order.

A still further object of the invention is to provide an improved switch especially adapted for use in electrical signaling systems in conformity with the preceding objects, in which the switch may be automatically operated in a rotative step-by-step movement by passage of a train, and will be yieldingly urged to the complete switch closing position in response to actuation by the passage of a train.

These, together with various ancillary features and objects of the invention, which will later become apparent as the following description proceeds, are attained by the present invention, a preferred embodiment of which has been illustrated, by way of example only, in the accompanying drawings, wherein:

2

Figure 1 is a top plan view of a portion of a railway track for trains, and showing the manner in which the novel signaling system may be associated with a crossing of the railway track;

Figure 2 is a top plan view, the cover being broken away to show the internal parts of a switch element forming a part of the invention;

Figure 3 is a view similar to Figure 2 but showing a second of the pair of switches forming a part of the invention;

Figure 4 is an end elevational view of the switch members of Figures 2 and 3, the same showing the actuating member for the switches;

Figures 5 and 6 are, respectively, vertical central longitudinal sectional views taken substantially upon the planes indicated by the section lines 5—5 and 6—6 of Figures 2 and 3 respectively;

Figures 7—9 are vertical transverse sectional views taken substantially upon the planes indicated by the section lines 7—7, 8—8 and 9—9 of Figure 3, respectively;

Figure 10 is a side elevational view of a rotary switch member forming a part of the switch unit of Figure 2;

Figures 11 and 12 are vertical transverse sectional views taken substantially upon the planes indicated by the section lines 11—11 and 12—12 of Figure 10, respectively;

Figures 13—16 are successive diagrammatic views illustrating the relative positions of the switches for operating the circuit means of the signaling system during successive phases of the operation thereof; and

Figure 17 is a perspective view of a stop or locking means forming a part of the rotary switches of this invention.

Reference is now made more specifically to the accompanying drawings which serve to illustrate one manner in which the principles of this invention may be advantageously and easily applied, the drawings illustrating the use of the invention for operating grade crossing or other signal lights of a railway.

Referring more particularly to Figure 1, it will be seen that there is disclosed at 10 a portion of a railway, which may be either a toy railway for which this invention is ideally adapted, or may actually constitute a commercial railway, if desired, the same being provided with a grade crossing or the like indicated at 12. A portion of the locomotive of a railway train, indicated at 14, is provided upon one side with a switch actuating element 16 in the form of a laterally extending rod, finger, or the like which, as the train passes one of the switch stations, is intended

to energize a switch element 18. A second switch element 20 is provided, these elements being disposed on opposite sides of the grade crossing 12 at a suitable distance therefrom to effect the desired result, as set forth hereinafter. While the element 18 is actuated by the finger 16 on one side of the locomotive 14, it is preferred to operate the other element 20 by a finger disposed on the opposite side of the train, this second finger being positioned either upon the locomotive or upon the rear car or one of the other cars of the train, as desired. It will be readily appreciated that the principles of this invention are not limited to the actual arrangement and positioning of the switches as shown, since, obviously, the switches could be successively operated in various ways. It is, however, essential for the purposes of this invention that the switches shall be so placed that they will be capable of being successively operated by the passage of the train by the switch so that as the train approaches the crossing and passes the first switch, the latter will be actuated, while after the train has completed its passage of the crossing, the passage of the train past the second switch will in turn actuate the latter.

The two switches are intended to control and operate in a novel manner, as set forth herein-after, two sets of electric signal lights, these two sets being indicated at 22 and 24 and disposed on opposite sides of the grade crossing. If desired, but one such set of lights could be provided, the principle of operation of the lights being the same.

Each of the pairs of lights 22 and 24 includes a "go" light 28 and a "stop" light 26. These two lights are intended to be operated in alternation, it being contemplated that at all times one of the lights will be illuminated. When the train is not in proximity to the crossing, it is understood that the "go" light will be illuminated, while during the period of time when the train is in close proximity to and passing through the grade crossing, the "go" light will be darkened and the "stop" light will be illuminated as set forth hereinafter.

It is obvious that various types of switches and circuit arrangements could be provided to effect the desired results. One very satisfactory arrangement has been illustrated in the accompanying drawings, making use of a pair of switch elements 18 and 20.

The two switches 18 and 20 are generally similar in their over-all construction, each consisting of a rotatable switch body having switch blades, together with stationary sets of contacts adapted to be contacted by the blades.

Referring now more particularly to Figures 3 and 6, it will be seen that the switch assembly 18 includes a suitable dielectric casing or switch box 30 having a removable closure 32 therefor. Rotatably journaled in this switch box, in a pair of walls of the same and extending beyond one of the walls, is a horizontally disposed shaft 34 which, upon its exposed end is provided with a switch actuating member 36 which may conveniently comprise a cruciform-shaped body having radially extending actuating arms 38. As illustrated, four such arms are provided, although the principles of this invention will admit of the use of any desired number of arms, it being, of course, necessary that the internal construction of the switch be changed to conform to the number of arms employed. In any event, the actuator member 36 is disposed in the path of travel

of the finger 16 on the locomotive, or the other actuating finger wherever positioned upon the train so that as the finger passes by the switch station, the finger will engage one of the arms 38 and impart a partial rotation to the switch actuating member and shaft. Successive passages of trains by the switch will cause a step-by-step rotation of the switch shaft and a series of successive operations of the switch as set forth hereinafter.

In the present invention, this step-by-step or partial rotation of the switch body is utilized to successively close sets of contacts within the switch box to control the various circuits forming a part of this invention.

In order to insure that the rotatable switch member will be always actuated into circuit closing position upon each actuating impulse of the finger 16 against the arm 38, a resilient stop or locking means is provided. This means preferably consists of a stationary cam body 40 secured to the interior of the switch box and concentric with the shaft 34, this cam body having a plurality of cam lobes or axial projections 42 together with cam recesses 44 therebetween. When the switch is designed to have four switch operations for each revolution of the switch shaft, the actuating member 36 will have four radial arms 38, while the cam member 40 will have four lobes and four recesses. A locking dog, which, as shown in Figure 17, may conveniently comprise an annular or drum-like body 46, is provided with an axial bore 48 slidably received upon the shaft 34 and having a keyway 50 adapted to slidably engage a pin 52 carried by the shaft whereby the body 46 has free axial sliding movement upon the shaft but is non-rotatably keyed thereon for rotation therewith. At its end facing the cam member 40, the locking member 46 has a pair of diametrically disposed axially extending locking lugs 54 which are adapted to rotate over the surface of the cam member 40, riding over the cam lobes 42 thereof and descending into the cam recesses 44 between the lobes. A spring member 56 abuts one end of the locking body 46 and yieldingly urges the latter into engagement with the locking cam 40. The engagement of the lugs 54 with the lobes and recesses, under the bias of the spring, will tend to resiliently maintain the lugs within the recesses and thus will rotationally lock or yieldingly position the shaft 34 in each of the switch-closing positions of the shaft.

It will thus be apparent that even if the member 36 is not actuated through a fully ninety degrees of rotation, the switch will automatically be yieldingly urged to the switch closing position when the lugs 54 pass over the crests of the cam lobes 42.

As so far described, the switch members 18 and 20 are of identical construction. However, modified rotary switch bodies are mounted upon the shaft 34 to effect the different circuit controlling operations of the two switch units. Each of these switch bodies consists of a dielectric cylinder or drum such as that indicated at 58 for the switch 18, and at 60 for the switch 20. Each of these drums is fixedly and non-rotatably secured to the shaft 34 within the switch box as by a fastening pin 62. The above-mentioned spring 56 which abuts the locking body 46 has its other extremity abutted against the adjacent end of the rotatable switch body 58 or 60, as shown in Figures 5 and 6.

Intermediate its ends, the rotatable switch

body 58 is provided with an annular flange or collar 64, while the rotatable switch body 60 of the switch member 20 has a pair of such annular flanges or collars 66 and 68, the collars 64, 66 and 68 being of identical construction whereby the showing of Figures 11 and 12 will be applicable to each of them.

Since the switch blades mounted upon each of the shoulders 64, 66, and 68 are identical, the same numbers will be applied to the corresponding blades throughout this description. As previously mentioned, the rotatable bodies 58 and 60, together with their shoulders are of a dielectric or insulating material, and a pair of diametrically disposed electrically conductive switch blades 70 and 72 are embedded in parallel faces on opposite sides of each of the shoulders, these blades being disposed at right angles to each other. The embedded blades are preferably flush with the annular surfaces of the shoulders, as will be readily apparent from Figures 5, 6 and 10.

The blades 70 and 72 constitute the movable contact members of the switch unit.

As shown in Figure 3, the stationary switch contact members comprise a U-shaped electrical terminal 74 having a binding post 76 extending through one wall of the switch box, the legs of the U-shaped terminal yieldingly embracing the opposite sides of the shoulder 64 for engaging the blades 70 and 72 during rotation of the switch body 58.

On the opposite side of the switch box there are provided a pair of contacts 78 and 80 each of a resilient nature and provided with binding posts 82 and 84, respectively. The contacts 78 and 80 embrace the opposite sides of the collar 64 for engaging the switch blades 70 and 72 thereon. The arrangement is such that the contact 74 will serve to continuously supply current from any suitable source such as that indicated by the storage battery 86 of Figures 13-16 to whichever of the switch blades 70 and 72 are in contact with the member 64. The arrangement of the blades 70 and 72 at right angles to each other will therefore cause the blades to alternately establish contact between the member 74 and one of the stationary terminals 78 and 80 for each ninety degrees of rotation of the shaft and of the switch body mounted thereon. Thus, the contact 74 will be electrically connected with the contact 78 and upon ninety degrees of rotation will be connected instead with the contact 80, and so on. Thus, for each ninety degree step of rotation of the switch body, the source of current 86 is alternately connected with the connector or binding post 82 or 84.

The switch member 20 is of identical construction with the switch member 18 previously described except for the actual construction of the switch body 60 which has two instead of one flange or collar thereon, each having a pair of perpendicularly disposed switch blades. However, the stationary contact arrangement is different with respect to the switch, since, as shown in Figure 2, there are provided a pair of U-shaped contacts 88 and 90 having binding posts 92 and 94 extending through the walls of the switch box, each of these U-shaped contacts embracing one of the collars on the switch body. Thus, the U-shaped contact 88 embraces the collar 66 while the contact 90 embraces the collar 68.

On the opposite side of the switch box of the switch 20 there is provided a centrally disposed U-shaped contact 96 having a binding post 98,

and a pair of separately disposed resilient contacts 100 and 102 having binding posts 104 and 106.

The U-shaped contact 96 is disposed between the collars and engages the switch blades 70 and 72 on the adjacent faces of the two collars, while the contacts 100 and 102 engage the opposite or outer sides of the collars, respectively engaging the rotary switch blades 70 and 72.

It is believed that the operation of the two sets of rotary switch blades with the sets of stationary contacts will be readily understood in view of the foregoing explanation of the operation of the switch contacts of the switch 18.

In order to better understand the manner in which the two switch assemblies are connected to each other and to the signal lights in accordance with this invention, reference is now made to the diagrammatic views of Figures 13-16. Although it will be understood that the switch members have rotary contacts, the diagrammatic views illustrate reciprocating switch elements in the interest of simplicity of illustration. The source of electrical supply 86 is connected to the

U-shaped contact 74 of the switch 18 by means of a conductor 108. Through the agency of the switch body 58 and the switch blades carried thereby, the stationary contact 74 is connected in alternation to the contacts 78 and 80 and through their binding posts 82 and 84 to a pair of electric conductors 110 and 112. The conductor 110 is, in turn, connected to a conductor 114, the conductors 110 and 114 being respectively connected to the stationary switch contacts 100 and 102 of the switch member 20, while the conductor 112 is connected to the U-shaped switch contact 96. Through the shoulders 66 and 68, the contacts 100, 96, and 102 are selectively connected to the contacts 88 and 90, the latter being connected by conductors 116 and 118, respectively, with the above-mentioned stop and go lights 26 and 28. The latter, in turn, are connected by a ground connector 120 to the source of electrical energy.

The operation of the switch signalling system will now be readily understood from the diagrammatic views of Figures 13-16. It is assumed that the showing in Figure 13 is that of the signalling system when no trains are in the vicinity of the grade crossing 12. At that time, the switch 18 is so positioned as to connect the terminal 74 with the terminal 78, whereby current is supplied to the conductors 110 and 114. However, the conductor 110 is not engaged by the switch blade of the member 66, but the conductor 114 and its contact 102 are in connection with the switch member 90, thereby establishing a circuit by means of a conductor 118 through the "go" light 28 whereby the latter will be energized to indicate that no train is in the vicinity of the crossing.

As a train approaches a crossing in the manner shown in Figure 1, the finger 16 upon the locomotive will impart a ninety degree turn to the actuator member 36 by engaging one of the spokes 38 thereof, thereby rotating the switch body 58 through one-quarter of the revolution. As a train approaches a crossing, it is assumed that the "go" light is on at the crossing and the "stop" light is deenergized. As the train approaches the switch member 18, the switch is moved to the position shown in Figure 13, thus energizing the circuit to the "stop" light and deenergizing the circuit to the "go" light. When the train has completed its passage of the cross-

ing, the switch actuator upon the end of the train will actuate the switch 20, thereby moving the light to the position shown in Figure 14 and break the circuit to the "stop" light while again energizing the circuit to the "go" light. It will now be seen that the switches are in their reversed positions, but that the signal lights are in their normal positions, awaiting the approach of the next train. When now the train again approaches the switch 18, the latter will be actuated and the signalling system will assume the position shown in Figure 15, with the "stop" light again energized until the train again passes a crossing, at which time the switch 20 will be actuated and the signalling circuits will be in the position shown in Figure 16, with the "go" light again energized and the "stop" light darkened.

Certain features of the invention are obviously applicable to other electrical systems than a railway signalling system, since this invention readily enables the selected actuation of alternate electric circuits from sequential actuation of remotely located switches.

Since, from the foregoing, the construction and advantages of this invention are readily apparent, further description is believed to be unnecessary.

However, since numerous modifications and equivalents will readily occur to those skilled in the art after a consideration of the foregoing specification and accompanying drawings, it is not intended to limit the invention to the exact embodiment shown and described, but all suitable modifications and equivalents may be resorted to which fall within the scope of the appended claim.

Having described the invention, what is claimed as new is as follows:

For use in a railway signalling system having vehicle carried switch actuating members, a rotary switch for step-by-step actuation by the suc-

cessive passage of vehicles comprising an insulating casing, a shaft journaled in said casing, one end of said shaft extending from said casing, a cruciform switch actuating member fixed on said extending end for engagement by said switch actuating member, a stationary cam member secured to the interior of said casing concentric with said shaft, a plurality of axially extending radial cam lobes on said stationary cam, a locking dog slidably and non-rotatably mounted on said shaft, a lug on said dog adapted to ride on said cam lobes, resilient means biasing said dog into contact with said cam, a dielectric drum fixed on said shaft, an annular flange on said drum, a pair of switch blades embedded in the opposite parallel faces of said flange, said blades being disposed at right angles to each other, a U-shaped contact terminal mounted in said casing, the legs of said U-shaped terminal resiliently engaging the opposite sides of said flange, a pair of contact terminals mounted on the opposed side of said casing, said contacts resiliently engaging opposite sides of said flange.
